Primary Examiner — Ruth McInroy(74) *Attorney, Agent, or Firm* — David Chen; DWC Law Firm, P.S.(57) **CLAIM**

The ornamental design for a stowed portable grill, as shown and described.

DESCRIPTION

FIG. 1 is a top perspective view of a stowed portable grill showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the stowed portable grill which form no part of the claimed design.
